WALL GROUND WORK STRIP

Application filed January 13, 1930. Serial No. 420,576.

This invention relates generally to improvements in building construction and more particularly to the provision of means for securing wall ground work such as wall board and the like in place.

One of the principal objects of this invention is to provide means of the above type in the form of a strip which, in addition to securing the wall ground work in place, also functions to separate adjacent sections of the ground work forming the wall and further operates to interlock the plastic material applied to the ground work with the strips to form a homogeneous mass.

A further advantageous feature of the present invention resides in the provision of an anchor strip capable of being readily deformed for securing the various sections of the wall ground work in angular relation to each other to form a corner assembly.

A still further object of this invention is to provide a strip of the above character which may be readily formed by a stamping or rolling operation and, as a consequence, lends itself to economical manufacture and also one which may be expediently secured to its support irrespective of slight surface variations of the latter.

With the foregoing as well as other objects in view, the invention resides in the novel construction of the strip and the manner in which it cooperates with the wall assembly to form a homogeneous mass.

In the drawings:

Figure 1 is a fragmentary perspective view illustrating one application of our improved anchor strip.

Figure 2 is a sectional view showing the manner in which the strip is secured to the stud members.

Figure 3 is a cross-sectional view through the strip showing the wall ground work in position.

Figure 4 is a plan view of a strip of metal illustrating the manner in which the strip is formed.

Figure 5 is a sectional view showing the application of the strip to an inner corner assembly.

Figure 6 is a view similar to Figure 5 showing

the application of the strip to an outer corner assembly.

Figure 7 is also a sectional view showing still another application of the strip.

Referring now to the drawings, it will be noted that there is illustrated in Figure 1 an anchor strip 10 having a body portion 11 substantially channel-shaped in cross-section with the leg portions 12 of the channel terminating in oppositely extending foot flanges 13. The foot flanges 13 cooperate with the leg portions 12 to form a rabbeted recess upon opposite sides of the base 14 of the channel for receiving the adjacent sections 15 and 16 of the wall ground work. The construction is such that the adjacent edges of the sections 15 and 16 abut against the legs 12 of the channel and, as a consequence, are spaced from each other a distance commensurate with the width of the base 14 of the channel. The width of the leg portions 12 preferably corresponds to the width of the sections 15 and 16 so that the outer surfaces thereof are substantially flush with the outer surface of the base portion 14 and forms in effect a continuation thereof.

In order to secure the sections 15 and 16 in place upon the strip, the base portion 14 of the latter is provided with a series of longitudinally spaced struck out tongues 17 and 18 adapted to project alternatively in opposite directions over the adjacent edges of the sections 15 and 16. As will be apparent from Figure 3 of the drawings, the major portions of the tongues are arranged flush with the exterior surface of the base 14 and the end portions thereof are bent upwardly as indicated by the reference character 18' to facilitate engagement of the wall ground work sections with the strip.

The opposed legs 12 of the channel are notched as indicated at 19 to form aligned substantially V-shaped openings 20 which, as shown in Figure 1, connect into suitable slots 21 formed in the base 14 of the channel intermediate the struck-out lugs 17 and 18. The arrangement is such that when a plastic material such as plaster is applied to the wall ground work, the material flows or is forced into the openings 20 and 21 and

forms with the strip an interlocking connection. It will also be noted that the plastic material is permitted to flow into the openings formed by striking out the tongues 17 and 18 so that these openings also serve to interlock the plastic material with the strip. Thus from the foregoing it will be observed that the strip, wall ground work and plastic material are rigidly secured together to form a homogeneous mass. The width of the slots are predetermined and are substantially equal to the width of the material therebetween and since it has been stated above that the notches are substantially V-shaped it will be apparent that the notches 20 and slots 21, in addition to performing the above described function, also provide means for breaking the strips to the desired lengths.

When the strip 10 is utilized in the manner illustrated in Figure 2, the end portions thereof may be slotted, as designated by the reference character 22, for receiving a portion of the stud members 23. In detail, this is accomplished by separating the end portions of the legs of the channel from the foot flanges and bending the latter outwardly to form a slot of sufficient dimension to permit the portions 24 of the studs to engage between the legs and flanges. In practice, it has been found that the above construction is sufficient to maintain the strips in assembled relation with the studs without the aid of any securing means.

Referring now more in detail to Figure 4, it will be noted that the strip 10 is developed from a single sheet of metal by first punching the openings 21 therein and striking out the tongues 17 and 18 and then fashioning the strip to the desired contour by a stamping or rolling operation to form the finished strip. In this connection it is to be noted that in fashioning the material to form the completed strip, portions of the openings 21 extend into the leg portions 12 of the channel 11 forming the openings 19 and 20.

In Figure 5 we have illustrated a strip 25 especially designed for inner corner assemblies to secure the sections 26 and 27 of the wall ground work in angular relation to each other. As shown, the strip is provided with flanges 28 and 29 extending at an angle to each other corresponding to the angular relationship of the sections 26 and 27 and adapted to engage the inner angular surfaces 30 and 31, respectively, of the stud member 32. The flanges 28 and 29 are connected together by means of a web 33 having portions 34 cooperating with the flanges 28 and 29 to form rabbeted recesses for receiving the sections 26 and 27. The adjacent edges of the sections are adapted to abut against the portions 34 of the web and are held in place by means of tongues 35 struck out from the cen-

tral portion 36 of the web at longitudinally spaced points and adapted to extend over the adjacent edge portions of the sections 26 and 27 in substantially the same manner as the tongues 17 and 18. The above strip may be formed from the strip 10, hereinbefore described, by bending the legs 12 of the channel from the position illustrated in Figure 1 to an angle of approximately 45° outwardly. The transformation of the strip 10 to the strip 25 is clearly illustrated in Figure 5 wherein the strip 10 is illustrated in dotted lines.

In Figure 6 we have shown a strip 37 especially designed for exterior corner construction. This strip comprises flanges 38 and 39 adapted to engage the exteriorly angular surfaces 40 and 41, respectively, of the stud member 42 with the longitudinal edges 43 of the flanges adjacent each other. Extending outwardly at substantially right angles to the flanges 38 and 39 are flanges 44 and 45, respectively, which form abutments for the adjacent edges of the ground work sections 46 and 47. The flanges 44 and 45 are connected together by means of a web 48 having the struck out tongues 49 adapted to extend over the adjacent edge portions of the sections 46 and 47 to secure the same in place. In this connection it is to be noted that the formation of the web 48 is substantially the same as the base of the channel 14 of the strip 11 in that it is provided with openings intermediate the tongues 49 for the reception of the plastic material.

The strip illustrated in Figure 7 is preferably identical in construction to the strip 10, hereinbefore set forth, with the exception that the foot flanges 13 are provided with extensions 50. The extensions are preferably flared outwardly from the outer edges of the foot flanges, as illustrated in Figure 7, and are adapted to engage a suitable support. The arrangement is such as to provide a spring base for the strip so that any variations in the surface of the support will be compensated for by the resiliency of the extensions. The above form of strip finds particular utility for use with steel joists wherein the lower member often times varies in level.

What we claim as our invention is:

1. A strip for use in building construction to secure adjacent sections of wall ground work in spaced relation to each other, said strip having a body portion substantially channel-shaped in cross-section with the legs of the channel forming abutments for the adjacent edges of the sections aforesaid, and tongues struck out from the base of the channel at longitudinally spaced points and arranged to extend over the adjacent edges of the said sections to secure the same in place.

2. A strip for use in building construc-

- tion having a body portion substantially channel-shaped in cross-section, said channel having the leg portions thereof terminating in oppositely extending foot flanges
 5 adapted to engage a support and cooperating with the said leg portions to form rabbeted portions for receiving adjacent sections of wall ground work, and tongues struck out from the base of said channel at
 10 longitudinally spaced points and arranged to extend alternatively in opposite directions over the adjacent edges of the sections aforesaid to hold the latter in place.
3. A strip for use in building construction
 15 to secure adjacent sections of wall ground work in spaced relation to each other, said strip having a body portion substantially channel-shaped in cross-section with the legs of the channel forming abutments for the adjacent edges of the sections aforesaid, the base of said channel having openings therein at longitudinally spaced points for receiving a plastic material applied to the ground work to form an interlocking connection
 20 between the strip and material and tongues projecting from the said base of the channel at points intermediate the openings therein and arranged to extend over the edges of the adjacent sections for securing
 25 the same in place.
4. A strip for use in building construction to secure adjacent sections of wall ground work in spaced relation to each other, said strip having a body portion substantially channel-shaped in cross-section with the legs of the channel forming abutments for the adjacent edges of the said sections, the base and leg portions of said channel having connecting openings therein at longitudinally spaced points for receiving a plastic material applied to the ground work to form an interlocking connection between the said material and strip.
5. A strip for use in building construction
 45 to secure adjacent sections of wall ground work in spaced relation to each other, said strip having a body portion substantially channel-shaped in cross-section with the legs of the channel forming abutments for the adjacent edges of the sections aforesaid, the said leg portions having aligned openings therein connecting into an opening formed in the base portion to permit the plastic material applied to the ground work to flow into the channel and form with the strip an interlocking connection, and tongues struck out from the base portion of the channel intermediate the openings therein and arranged to project alternatively in opposite directions over the adjacent edge portions of the sections for securing the same in place.
6. A strip for use in building construction to secure adjacent sections of wall ground work in spaced relation to each other, said strip having a body portion substantially

channel-shaped in cross-section with the legs of the channel forming abutments for the adjacent edges of the sections aforesaid, and tongues struck out from the base of the channel at spaced points and arranged to extend over the adjacent edges of the said sections to secure the same in place, the openings formed by said struck out portions permitting the plastic material applied to the ground work to flow into the channel and form therewith an interlocking connection.

7. A strip for use in building construction to secure adjacent sections of wall ground work in angular spaced relation to each other, said strip having side flanges arranged at an angle to each other corresponding to the angular relation of the sections aforesaid and also having a web connecting said flanges, said web having portions adjacent the flanges cooperating therewith to form rabbeted recesses for receiving the said sections and tongues struck out from the said web and arranged to extend over the adjacent edges of said angularly arranged sections to secure the same in place.

8. A strip for use in building construction to secure adjacent sections of wall ground work, said strip comprising a body portion disposed between the adjacent edges of the sections and having spaced parts forming abutments for the adjacent edges, and tongues struck out from the body portion for clamping the sections to the abutments aforesaid.

In testimony whereof we affix our signatures.
